UNITED STATES PATENT OFFICE.

ALEXANDER H. REVELL, OF CHICAGO, ILLINOIS.

BED.

SPECIFICATION forming part of Letters Patent No. 687,436, dated November 26, 1901.

Application filed July 30, 1898. Serial No. 687,332. (No model.)

To all whom it may concern:

Be it known that I, ALEXANDER H. REVELL, of Chicago, in the county of Cook and State of Illinois, have invented a certain new and 5 useful Improvement in Beds, of which the following is a specification.

This invention relates to beds, and has for its object to provide a double bed which shall be more comfortable in use than such beds 10 as ordinarily constructed, while at the same time no increase in the amount of space required will be necessitated.

In double beds as ordinarily constructed it has been found that when the bed is used by 15 two occupants of unequal weight the bed is unequally depressed and rendered uncomfortable for the occupants on that account. It is also frequently the case that in modern apartment-houses as now constructed the restricted space renders it impossible to obviate 20 the difficulty pointed out by the use of two separate beds, the bedrooms being usually too small to furnish sufficient space for them.

It is the object of my invention to overcome 25 these difficulties and provide a double bed which while occupying only the amount of space required for an ordinary bed will have all the advantages of two separate single beds.

30 In the accompanying drawings, Figure 1 is a plan view of a bed embodying my invention, the upholstering being removed. Fig. 2 is a similar view of the completed bed. Fig. 3 is a transverse vertical sectional view taken on the line 3 3 of Fig. 2 and on an enlarged 35 scale; and Fig. 4 is a view similar to Fig. 3, illustrating a modification.

In the said drawings, 10 indicates the bed-bottom or rigid frame, which in the particular 40 form of bed shown in Figs. 1, 2, and 3 is composed of vertical pieces 11 at the sides and ends of the bed, and transverse slats 12 cross the bottom of the frame at suitable intervals. From the vertical pieces 11 there 45 extend outward laterally in a horizontal direction pieces 13. Within the box-like bottom or frame thus formed are mounted the bed-springs 14, which are of any approved form and which are tied or stayed in the 50 manner indicated in Fig. 1 of the drawings or in any other suitable manner. The outer rows of springs 14 rest upon the horizontal

pieces 13, as shown in Fig. 3. Upon the top of these springs rests the bed proper or cushion 15, which is stuffed or upholstered in any 55 approved manner, but which is made on two separate and independent sections extending longitudinally of the bed, the line of division between them being central.

The edges of the bed proper are stiffened 60 by means of strips of ratan or other suitable material, as indicated at 16, and the two independent sections of the bed proper are each covered with a suitable covering 17, of ticking or other cloth. These two sections 65 of covering 17 are extended downward between the two sections of the bed to the bottom of the frame or to a suitable brace 18, extending longitudinally thereof at the center, and serve to prevent the edges of the two sections 70 or the springs adjacent thereto from coming into contact with each other, and thus affecting the independence of operation of the two sections.

It will be seen that a bed constructed in 75 the manner just described comprises in a single rigid frame of the size of an ordinary double bed two independent bed-sections which will accommodate two persons of widely-varying weight without the depression of one section of the bed in any way affecting the other section or the comfort of the person occupying it. The bed takes up much less room than two single beds of sufficient width to comfortably accommodate the users 85 thereof and is thus adapted for use in localities where space is restricted.

Obviously the details of the construction just described may be varied without departing from the principle of my invention. In 90 illustration of this I have shown in Fig. 4 a modified construction in which the horizontal pieces 13 are omitted and the frame or bed-bottom is equal in its external dimensions to those of the bed proper. Moreover, in this 95 figure of the drawings I have illustrated the frame or bed-bottom as being made in two sections divided in a central longitudinal line and hinged together, as indicated at 19. In this structure of course the frame or bed-bottom is rigid when in use or when in place in the bedstead, the hinged structure being adapted for the purpose of enabling the bed 100 to be folded, so as to occupy less space in

transportation. In view of these and other obvious modifications I do not wish to be understood as limiting myself strictly to the precise details hereinbefore described, and 5 shown in the drawings.

I am aware that heretofore it has been proposed to employ a specially-constructed bedstead having transverse rails or ways upon which are mounted two separate bed-bottoms 10 or mattress-supports slidably mounted on said rails, so as to be capable of being moved toward and from each other and each carrying a separate mattress. I am also aware that it has been proposed to employ a specially-constructed bedstead the bottom of 15 which comprises two separate parts or frames each adapted to receive a mattress and united to a common head-frame and foot-frame. In each of these constructions, however, there 20 is necessarily comprised a specially-constructed bedstead, whereas a bed constructed in accordance with my invention is adapted for use in the ordinary bedstead without any changes or modifications in the bedstead or 25 the necessity of any special appliances for supporting the bed in the bedstead. I am also aware that it has been proposed to construct a bed or bed-bottom in a plurality of transversely-extending sections hinged together 30 so as to fold into a comparatively small compass; but in this construction each section is used in common by the two occupants of the bed, so that the objections avoided by my improved construction are in no 35 way obviated by such transverse division of the bed-bottom.

I claim--

1. A bed comprising a rigid box or tray

like frame composed of inclosing sides and transverse bottom slats and adapted to fit 40 and be supported by an ordinary bedstead, and two independent bed-sections mounted within said frame and extending longitudinally 45 therein, each of said sections comprising a series of spiral springs secured at their lower ends to said slats, and a mattress for each section and conforming to and resting on the springs thereof, said bed-sections being entirely disconnected from each other along their adjacent sides, substantially as 50 and for the purposes set forth.

2. A bed comprising a rigid box or tray like frame composed of inclosing sides and transverse bottom slats, said frame being divided longitudinally to afford similar sections 55 foldable back to back and hinges connecting said sections, and the whole being adapted to fit and to be supported by its ends upon an ordinary bedstead, and two independent bed-sections mounted within said 60 frame and extending longitudinally therein, each of said sections comprising a series of spiral springs secured at their lower ends to said bottom slats, a mattress for each section, and a covering for each mattress extending 65 downwardly over the adjacent sides of and between said sections, and the said sections being wholly disconnected at their adjacent sides whereby they are rendered capable of independent action while mounted 70 upon a frame common to both, substantially as described.

ALEXANDER H. REVELL.
